UNITED STATES PATENT OFFICE.

WALTER B. SCOTT, OF MARBLEHEAD, MASSACHUSETTS.

TOY WINDMILL.

Application filed June 15, 1925. Serial No. 37,252.

My invention relates to wind toys and comprises particularly such a toy wherein a wind wheel operates a rocking member and wherein the latter functions to keep the wind wheel 5 in operative position.

This object is attained by the mechanism illustrated in the accompanying drawing, in which Figure 1 is a side view of a wind mill; Fig. 2 is a top plan view of a wind mill; Fig. 10 3 is a perspective view of a wind mill.

Similar characters refer to similar parts in the several figures.

A represents a base. This base is mounted to rotate in a horizontal plane. To this end 15 there is employed a pivot rod B received in a suitably located socket in the base. It is intended that the base be pivotally mounted upon a garage roof, a fence post or elsewhere so that the wind wheel may be rotated by the 20 wind. Upon the base is a wind mill comprising a tower C carrying a shaft D horizontally mounted and journaled for rotation near the top of the tower. The shaft extends fore and aft and at its front end in front of 25 the tower carries fixed thereto, a wind wheel E. To the rear of the tower the shaft is provided with an offset crank F. A toy sail 30 boat G is mounted on the base to the rear of the mill by a pivot H extending transversely of the base to thereby permit the rocking of 35 the boat in a vertical plane. This vertical rocking is effected by means of a pitman I connected to the boat at its bow and the aforesaid crank. It will be seen that when the wind wheel swings into the wind it will rotate the shaft and by means of the crank and pitman the sail boat is made to rock on its pivot.

A toy having parts described above combines a picturesque tower with a rotating wind wheel and a miniature sail-boat carrying a relatively large sail. The rotation of the wind-wheel rocks the sail-boat through the agency of the mechanical connections, the rocking motion simulating motion of the boat on waves of the sea. The spars carrying the sail diverge in a vertical plane from the mast of the boat in much the same way as the lines of a weather-vane diverge in a vertical plane. This divergence gives the greatest vertical extent in that part of the sail 40 most remote from the mast and renders the sail an efficient means to swing the combined toy about its vertical pivot and thereby hold the wind-wheel into the wind. 45

It will thus be seen that the toy-boat serves 50 very nicely the purpose of a tail or a vane to hold into the wind the wind-wheel, the rotation of which gives the boat its rocking motion. 55

What I claim is:

A wind toy comprising a wind wheel, a 60 rocking sailboat having a sail, a vertical pivot therebetween about which both wheel and sailboat simultaneously revolve, means connecting the wheel and boat whereby axial rotation of the former rocks the latter, the shape of the sail being such as to have a relative large height at a point removed from the vertical pivot whereby the sail simulates 65 and has the function of the vane of a windmill. 70
